UNITED STATES PATENT OFFICE.

CHARLES ARMSTRONG JOHNSON, OF NASHVILLE, TENNESSEE.

VENDING MACHINE.

Application filed May 16, 1927. Serial No. 191,720.

My invention relates to improvements in vending machines and refers particularly to a machine for vending packages, cartons or single units of oblong shape, making the machine highly desirable for vending sandwiches, boxes of cigars or cigarettes, candy and in fact any package which could be dispensed by my machine.

One object of the invention is the provision of a machine which will comprise a small number of parts insuring simplicity, durability and cheapness of construction, and which will provide a mechanism which will be absolutely certain and reliable in operation.

Another object of my invention is the provision of a machine of this character which cannot get out of order and which will prevent fraudulent operation and at the same time prove entirely efficient when the proper coin has been deposited in the machine.

Another object of my invention is the provision of a vending machine which will be comparatively small and compact in size to occupy a small space while having a large containing capacity and which in every respect will be efficient, practical and very desirable for the intended purposes.

With these objects in view my invention consists of a vending machine embodying novel features of construction and combination of parts substantially as described and claimed and as shown in the accompanying drawings, in which:

Figure 1 represents a top plan view of a vending machine constructed in accordance with my invention.

Fig. 2 represents a vertical sectional view of the machine, the parts being in normal position before the insertion of a coin.

Fig. 3 represents a front elevation of the machine.

Fig. 4 represents a vertical sectional view of the machine, the parts being in the position they assume after the coin has been received and deposited and the ejecting lever is forcing the package out or delivering said package.

Fig. 5 represents a vertical sectional view the parts being in the position they occupy when the package is being carried forward for delivery.

Fig. 6 represents a detail view on an enlarged scale of the ejecting lever, and

Fig. 7 represents a detail view of the coin receiver and push pin guide, showing in

dotted line the position of the coin delivery chute.

I have shown in the accompanying drawings a machine providing twin hoppers to receive the packages or cartons and with twin mechanism for operating upon the separate packages but it will be understood that the machine may be made of a single or plurality capacity as may be found necessary and desirable.

In carrying my invention into effect I provide the vertical container or hopper 1, which is provided with a glass front 2, and may have the back closed, or such back may be fastened by suitable means 3 to a wall or other support, while the hopper is provided with the division wall forming the bottom 4, formed with the slot 5, while said wall is further provided with the inclined portion 6, forming with the upper spaced wall 7, the delivery chutes 8, which lead to the discharge opening 9, in the lower portion of the hopper, said opening being closed by the hinged door or flap 10, while the compartment or chamber 11 is provided in the lower portion of the casing and in which the operating mechanism is placed.

From each side of the casing leads the coin chutes 12, whose mouth or entrance 13, is outside the casing, while the discharge portion 14, is contiguous to the coin receiving pockets 15, which pockets thus receive directly from the coin chute the coin and also in the closed wall 16 of said coin receivers is an opening 17, in which bears the push rod 18, one end of which is formed with a fork 19, which acts to engage the coin 20, while its outer portion passes through a sleeve 21, and is provided with a handle or button 22, a coil spring 23, being placed around the push rod and bearing against the wall 16, and a stop 16', for the purpose of returning the push rod to normal position.

From this construction it will be understood that the coin is deposited in one of the chutes and falls into the coin receiver in front of the fork 19, of the push rod, as shown in Figs. 2 and 5 and upon pressure inward of the push rod as shown in Fig. 4, the fork 19, engages the coin 20, and presses it against the yoke 24, of the ejector member 25, which is pivoted at 26, and carries at its upper end the spring actuated package engaging member 27, which as shown in Fig. 4 acts to push the package through the delivery chute and as shown in Fig. 5, said

package engaging member bears against the package 28 and as the ejector lever or member 25 moves outward, pushes said package toward the delivery opening, said ejector member having connected to its rear portion at 29, one end of the coiled spring 29 while at 30 the other end of said spring is connected to the casing, said spring acting to hold the ejector member in normal 10 position.

The operation of my machine will be readily understood from the foregoing description taken in connection with the drawings and it will be apparent that the parts 15 are in normal position as shown in Fig. 2, and upon the discharge of a coin into the coin receiver said coin falls between the fork on the push rod and the yoke at the lower end of the ejector member, the push rod is then 20 moved inward pushing the coin against the yoke and moving the ejector member to the positions shown in Figs. 4 and 5 effecting the delivery of the package, and in the event no coin is deposited in the machine the push 25 ing inward of the push rod will move the inner forked end thereof through the yoke in the ejector member without operating the machine.

It is evident that a machine constructed 30 in accordance with my invention will prove thoroughly practical and efficient for vending merchandise in packages or cartons and will prove highly desirable and useful for the purposes intended.

35 I claim:

1. A vending machine, consisting of a hopper or container, a bottom wall in said container having an inclined portion and provided with a slot, a chute above said in-

clined wall or portion, a door for closing 40 said chute, a coin delivery chute having its entrance outside the casing and its discharge in the lower portion of said casing, a coin receiver adjacent the discharge portion of the chute, a push rod mounted in the casing 45 and in said coin receiver, an ejector lever having its lower portion formed with a yoke, a spring actuated foot pivoted to the upper end of said ejector lever, and a spring 50 for returning said lever to normal position.

2. A vending machine, consisting of a casing having its upper portion providing a hopper and its lower portion forming a mechanism and coin receiving compartment, a coin chute in communication with the 55 lower portion of the hopper, a hinged door for closing communication between the chute and hopper, a slotted bottom in said hopper, an ejector lever pivoted in the lower portion of the casing, a yoke formed on the 60 lower end of said lever, a pivoted spring actuated foot forming a package engaging member and mounted on the upper end of the pivoted ejector lever, a spring connected to the lever and casing to return 65 said lever to normal position, a coin receiver adapted to receive the coin from the delivery chute and to normally receive the yoke on the ejector lever, a push rod having 70 a fork at its inner end to engage a coin and force said coin against the yoke to move the ejector lever, and a spring for normally retaining the push rod outward with reference to the casing.

In testimony whereof I hereunto affix my 75 signature.

CHARLES ARMSTRONG JOHNSON.
